[57] CLAIM

The ornamental design for a hilt portion of a scanner, as shown and described.

DESCRIPTION

FIG. 1 is a front isometric view of a hilt portion of a scanner showing our new design;

FIG. 2 is a front isometric view of FIG. 1 showing a head portion removed;

FIG. 3 is a front elevational view of FIG. 1;

FIG. 4 is the front elevational view of FIG. 3 showing the head portion removed;

FIG. 5 is a rear elevational view of FIG. 1;

FIG. 6 is a top plan view thereof;

FIG. 7 is a bottom plan view thereof;

FIG. 8 is the bottom plan view of FIG. 7 showing a handle removed; and,

FIG. 9 is the left side elevational view of FIG. 1, the right side elevational view being a mirror image thereof.

The broken lines in the Figures are for illustrative purposes only and form no part of the claimed design.
